UNCOUPLING MECHANISM.

1,417,547.

Specification of Letters Patent. Patented May 30, 1922.

Application filed October 6, 1921. Serial No. 505,694.

To all whom it may concern:

Be it known that we, ISAAC H. MILLIKEN and WILLIAM J. REGAN, citizens of the United States, residing, respectively, at Aspinwall, in the county of Allegheny and State of Pennsylvania, and Pittsburgh, in the county of Allegheny and State of Pennsylvania, have invented certain new and useful Improvements in Uncoupling Mechanism; and we do hereby declare the following to be a full, clear, and exact description of the invention, such as will enable others skilled in the art to which it appertains to make and use the same.

15 Our invention relates to uncoupling mechanism for causing the lock of a car coupler to perform an unlocking movement. While the invention is especially designed to provide means well adapted for application to 20 car couplers of the Master Car Builders' standard D-type employing a bottom operated lock, mechanism embodying the invention may be also used with other types of couplers as well.

25 The principal object of the invention is to provide a simple, compact and efficiently and reliably operating uncoupling mechanism that may be easily assembled or disassembled and in which the parts mutually interlock to prevent their accidental disassociation in service.

The principal feature of the invention, generally stated, consists in actuating the lock of a car coupler by means of a rotatable 35 member which is supported rearwardly of said lock by means adapted to swing lengthwise of the coupler and to move with the latter lengthwise of the car.

A further feature of the invention consists in causing the lock of a car coupler to 40 perform an unlocking movement by means of a rotatable member which is swingingly supported at its center of rotation by means movable with the coupler lengthwise of the car and adapted to swing in said lengthwise direction.

Another feature of the invention resides in actuating the lock of a car coupler by 45 means of a rotatable member which is swingingly supported rearwardly of the lock by a member interlockingly connected to said rotatable member and said coupler in a manner permitting it to swing lengthwise of the latter.

As will hereinafter appear, there are other 55 features of invention involving particular combinations of parts and special features of construction.

In the drawings illustrating the preferred form of the invention, the scope whereof is 60 pointed out in the claims,

Figure 1 is a view, partly in side elevation and partly in vertical section, of an uncoupling mechanism constructed in accordance with the invention, the coupler shown 65 being the well known Master Car Builders' standard D-type.

Figure 2 is a detail sectional view on the line 2—2, Fig. 1, portions of the uncoupling levers and of the coupler carrier iron and 70 coupler being broken away.

Figure 3 is a detail sectional view on the line 3—3, Fig. 1, portions of the uncoupling levers being broken away.

The car coupler 1 is provided with a lock 2 75 constructed and operating like the locks employed in couplers of this type. Movable connected to the lower end of the lock 2 and projecting downwardly through the lower wall of the coupler head is a link 3 which is 80 pivotally attached at its lower end to a lock lift lever 4 that is itself pivotally mounted upon the under side of the coupler. The link 3 and its pivoted lock lift lever 4 preferably conform in structure and mode of 85 operation to the corresponding devices of the standard D-type coupler. If the coupler is designed to have a wide range of lateral swinging movement it may be formed near the rear end of its shank with a pivot pin 90 opening 5 for receiving a tail pin (not shown) whereby the coupler may be pivotally connected to the draft gear of the car.

Movably connected to the lock lift lever 4 is a vertically rotatable member 6 which 95 is swingingly supported rearwardly of the coupler lock 2 by a member 7 adapted to swing lengthwise of the car, the latter member being connected to the coupler 1 so as to be movable therewith in said lengthwise 100 direction. The swinging supporting means 7 is preferably formed at its lower end with a hook 8 for cooperating with an eye 9 with which the vertically rotatable member 6 is furnished, a floating center of rotation 105 for the member 6 thus being provided. At its upper end the supporting member 7 may be conveniently fashioned with a hook 10

which cooperates with an eye 11 that is rigidly secured to the coupler 1, as for example by being cast integrally therewith. The hook 10 is designed to interlock with the eye 11 to prevent their accidental disassociation when the parts are assembled, the end of said hook being for this purpose provided with a portion 12 which is adapted to engage the eye 11 and thus prevent the detachment of the swinging member 7 when the parts are in normal operative relation.

As a means for interlocking connecting the vertically rotatable member 6 to the pivoted lock lift lever 4, the member 6 is preferably provided at its forward end with a hook 13 adapted to enter the eye or opening 14 with which the member 4 is customarily formed. At its rear end below the eye 9 the rotatable member 6 may be provided with a centrally disposed recess 15 which opens laterally on opposite sides so as to receive the upwardly extending inner ends 16 of rotatable uncoupling levers 17 by which the member 6 is preferably actuated to cause it to perform an unlocking movement. These uncoupling levers extend toward the sides of the car and may be and preferably are of the well known form illustrated in the I. H. Milliken Patent No. 1,184,116, dated May 23, 1916. The recess 15 may, as shown, be somewhat wider at the bottom than at the top so as to permit either of the uncoupling levers 17 to be operated independently of the other.

If desired the coupler 1, instead of being supported directly by the coupler carrier iron 18, may slidably bear upon a coupler saddle 19 which is mounted upon the carrier iron so as to move transversely of the car when the coupler swings laterally.

In assembling the mechanism the hook 10 of the swingingly supported member 7 is hooked through the eye 11 carried by the coupler. The hook 13 of the rotatable member 6 is then hooked through the opening 14 in the pivoted lever 4, which latter is temporarily disconnected from the coupler, and the member 6 is hung upon the hook 9 of the swinging support. The upwardly extending inner ends 16 of the uncoupling levers 17 are then inserted in the recess 15 of the member 6 and their outer ends are supportingly engaged with brackets at the sides of the car in the usual manner. When in assembled relation the parts of the mechanism are interlocked so that their accidental disassociation is prevented.

When either of the uncoupling levers is rotated by the trainman its upstanding portion 16 engages the rear end of the member 6 and causes the latter to perform an unlocking rotation. During this unlocking movement the member 6 rotates or pivots upon the hook 8 at the lower end of the swinging support 7 while the latter swings

lengthwise of the car as may be necessary to permit the forward end of the member 6 to conform to the path of travel of the eye 14 of the pivoted lock lift lever 4.

We claim:

1. In an uncoupling mechanism, the combination with a car coupler and its lock, of means for moving said lock to unlocked position, said means involving a rotatable member operatively connected to said lock, 75 means for actuating said rotatable member, and means coextensively movable with said coupler lengthwise of the car and adapted to swing in said lengthwise direction for supporting said rotatable member rearwardly of said lock.

2. In an uncoupling mechanism, the combination with a car coupler and its lock, of means for moving said lock to unlocked position, said means involving a rotatable member operatively connected to said lock and extending rearwardly therefrom, means for actuating said rotatable member, and swinging means for pivotally supporting said rotatable member rearwardly of said lock, said swinging means being movable with said coupler lengthwise of the car and being adapted to swing in said lengthwise direction.

3. In an uncoupling mechanism, the combination with a car coupler and the lock thereof, of means for moving said lock to unlocked position, said means involving a rotatable member operatively connected to said lock, means for actuating said rotatable member, and means for movably connecting said rotatable member to said coupler rearwardly of said lock, said last named means having a hook and eye connection with said coupler and with said rotatable member and being movable lengthwise of the car with said coupler.

4. In an uncoupling mechanism, the combination with a car coupler and its lock, of means for moving said lock to unlocked position, said means involving a rotatable member operatively connected to said lock and extending rearwardly therefrom, means for actuating said rotatable member, and means adapted to swing lengthwise of said coupler for swingingly supporting said rotatable member rearwardly of said lock, said swinging means being movable with said coupler lengthwise of the car.

5. In an uncoupling mechanism, the combination with a car coupler and its lock, of means for moving said lock to unlocked position, said means involving a rotatable member operatively connected to said lock and extending rearwardly therefrom, means for actuating said rotatable member, and means supported by said coupler for swingingly supporting said rotatable member rearwardly of said lock, said last named means being movable with said coupler

lengthwise of the car and being adapted to swing lengthwise of said coupler.

6. In an uncoupling mechanism, the combination with a car coupler and its lock, of means for moving said lock to unlocked position, said means involving a member pivotally connected to said coupler, a link operatively connecting said pivoted member to said lock, a vertically rotatable member movably connected to said pivoted member and extending rearwardly of said lock, an uncoupling lever engaging and adapted to actuate said rotatable member, and means supported by and adapted to swing lengthwise of said coupler for supporting said rotatable member rearwardly of said lock.

7. In an uncoupling mechanism, the combination with a car coupler and its lock, of means for moving said lock to unlocked position, said means involving a rotatable member operatively connected to said lock, means for actuating said rotatable member, and means movably connected to said rotatable member at the center of rotation of the latter for swingingly supporting said rotatable member, said last named means being supported by and adapted to swing lengthwise of said coupler.

8. In an uncoupling mechanism, the combination with a car coupler and its lock, of means for moving said lock to unlocked position, said means involving a vertically rotatable member operatively connected to said lock and having a recess adapted to receive an uncoupling lever and provided at its center of rotation with an eye adapted to receive a hook member, an uncoupling lever extending into said recess and adapted to actuate said rotatable member, and a hook member cooperating with said eye and supported by and adapted to swing lengthwise of said coupler for swingingly supporting said rotatable member.

9. In an uncoupling mechanism, the combination with a car coupler and its lock, of means for moving said lock to unlocked position, said means involving a rotatable

member operatively connected to said lock and having a recess adapted to receive an uncoupling lever and provided at its center of rotation with an eye adapted to receive a hook member, an uncoupling lever extending into said recess and adapted to actuate said rotatable member, and a hook member cooperating with said eye for swingingly supporting said rotatable member, said hook member being adapted to swing lengthwise of the car.

10. In an uncoupling mechanism, the combination with a car coupler and its lock, of means for moving said lock to unlocked position, said means involving a rotatable member operatively connected to said lock, means for actuating said rotatable member, and means supported by and adapted to swing lengthwise of said coupler for supporting said rotatable member, said last named means and said coupler being interlockingly connected.

11. In an uncoupling mechanism, the combination with a car coupler and its lock, of means for moving said lock to unlocked position, said means involving a member pivoted to said coupler, a link operatively interposed between said pivoted member and said coupler, a rotatable member movably connected to said pivoted member and having a recess adapted to receive an uncoupling lever and provided at its center of rotation with an eye adapted to receive a hook member, an uncoupling lever extending into said recess and adapted to actuate said rotatable member, and a swinging hook member adapted to support said rotatable member rearwardly of said lock, said hook member being connected to said rotatable member through said eye and being movably attached to said coupler through a hook and eye connection.

In testimony whereof we affix our signatures.

ISAAC H. MILLIKEN.
WILLIAM J. REGAN.
